UNITED STATES PATENT OFFICE.

HARLAN W. HOW, OF BUFFALO, NEW YORK, ASSIGNOR TO BUFFALO FOUNDRY & MACHINE COMPANY, OF BUFFALO, NEW YORK, A CORPORATION OF NEW YORK.

DRYING AND COOLING APPARATUS.

Application filed December 26, 1923. Serial No. 682,837.

This invention relates to a cooling and drying apparatus which embodies in its general organization a rotary shell or drum through which the material to be treated is passed from one end to the other and during this passage is subjected either to a heating or cooling medium and elevated within the shell during such passage, so as to thoroughly expose all parts of the material to the heating or cooling medium and thus facilitate finishing of the product.

In devices of this character as heretofore constructed the material under treatment engaged directly with the inner side of the wall or shell of the apparatus and this necessitated dismounting the entire apparatus including the dismembering of its bearings, driving mechanism, and so forth, whenever the shell or wall required renewal. In such apparatus as heretofore constructed, the temperature insulation was usually applied to the outer side of the shell which is objectionable by reason of the fact that it was difficult to firmly attach such insulation on the exterior of the shell and this resulted in the insulation frequently becoming separated from the shell and falling off and necessitating frequent repairs.

It is the object of this invention to provide an apparatus of this character in which the temperature insulation is arranged on the inner side of the shell where the same cannot become detached therefrom and also to provide the shell on its inner side with a lining which receives the wear and is capable of being renewed from time to time whenever this lining becomes worn out, thereby enabling the main shell or wall to be employed continuously and avoiding the necessity of dismembering the apparatus to any considerable extent when repairs or making replacements due to wear must be effected.

In the accompanying drawings:

Figure 1 is a vertical longitudinal section showing a practical embodiment of my invention in a rotary drier or cooler. Figure 2 is a vertical cross section of the same on an enlarged scale taken on line 2-2, Figure 1. Figure 3 is a fragmentary cross section of the shell, taken on an enlarged scale, the temperature insulations and internal lining on the same and also the material lifting blades or buckets mounted on the inner side of the shell.

Similar characters of reference refer to like parts in the several views.

The numeral 10 represents the cylindrical shell, drum or wall of the apparatus which is preferably constructed of sheet metal in the manner now commonly practiced, and rotatable about an axis which is either inclined slightly from its front end toward its rear end relatively to the horizontal, as shown in Figure 1, or may be arranged horizontally or in any other desired position as best suits the particular material which is to be treated. This shell may be rotatably supported by any suitable means, but in the preferred construction this is accomplished by providing the shell on its periphery near its front and rear ends with circumferential tires or rings 11, 12 which run on supporting rollers 13 engaging with the underside of the tires and mounted in any suitable manner upon base blocks 14.

In the present instance, the material is assumed to enter at the front end 15 of the shell which is elevated and discharged therefrom at its depressed rear end 16. When the material under treatment is to be heated, this may be accomplished by conducting heat from an oven 17 into the depressed rear end of the shell from whence it passes forwardly through the latter and is carried away from the elevated front end thereof into a stack or chimney 18. Various means may be employed for rotating this shell by power, but as the same form no part of this invention no particular reference will be made to them.

Arranged lengthwise on the inner side of the shell at different points circumferentially thereof are a plurality of metal ribs, each of which is preferably constructed of L-shape or in the form of an angle iron and arranged with its outer base flange 19 substantially parallel or concentric with the shell and adjacent to the inner side thereof, while its inner flange 20 projects radially inward from one edge of the base flange. In order to reduce the transmission of temperature from the interior of the shell to the outer side thereof through the medium of these ribs, a heat insulating strip 21 consisting preferably of asbestos is interposed between the base of each rib and the inner side of the shell and rivets 22 are passed through the shell, the base of each rib and the intervening temperature insulating strip 110

21 for the purpose of firmly uniting these members, as best shown in Figure 3. Temperature changes within the shell are also prevented from reaching the exterior of the 5 same along the spaces between the adjacent ribs by means of a temperature insulation 23 which is preferably constructed of segmental form and engaged at its opposite longitudinal edges with the opposing sides of 10 two adjacent ribs while its outer side engages with the inner side of the adjacent part of the shell.

This segmental temperature insulation is 15 preferably constructed of cellular asbestos, as shown in Figure 3, but if desired any other suitable temperature insulation may be used such as magnesia. Upon the inner edge of the radial flange of each rib is mounted a lifting wing, blade or bucket 20 24 which is preferably constructed of sheet metal. The inner side of the segmental temperature insulation between adjacent ribs is covered by a lining 25 of metal which is of segmental form and preferably concentric with the shell and constructed of sheet metal. Each of these segmental lining sections is detachably mounted on the adjacent ribs of the shell so that the same can be removed therefrom when required by providing the longitudinal lining section 25 25 with inwardly projecting flanges 26 and 27, the flange 26 engaging with one side of the lifting blade 24 which is mounted on one of the respective pair of ribs, while the 30 flange 27 engages with the adjacent side of the radial flange of the rib upon which the other lifting blade of the respective pair is mounted. The radial flange of each rib, the lifting blade 24 and the two flanges 26, 27 of the proximate lining sections 25 on 35 opposite sides of the same are detachably connected with each other by means of bolts 28 passing through these members, as best shown in Figure 3.

40 Obviously cold air or air of ordinary temperature may be conducted through this shell by any suitable means if it is intended to cool the material under treatment instead of heating and drying the same, it being understood that the material while passing from the inlet to the outlet of the shell is 45 repeatedly lifted by the blades or buckets, so as to expose the material to the action of the hot air, cold air or other medium which is intended to act upon the material.

When this apparatus is in use, the material under treatment which passes through the shell engages with the inner sides of the lining sections 25 so that any wear resulting from the attrition of this material will be taken by these lining sections, and when the same are worn out it is possible to easily renew them and thereby save the shell or main wall 10 from such wear. Such renewal can be effected quickly without the

necessity of dismounting the shell itself, thereby enabling such renewal to be effected economically and without prolonged interruption in the use of the apparatus which otherwise would be necessary.

70 Furthermore, by arranging the temperature insulation on the inner side of the shell in the manner shown and described, this insulation is held firmly in place and is not liable to become dislodged when the machine is in use, thereby enabling the same insulation to be used continuously without requiring any replacement and thus further increasing the economical operation of the machine.

75 Moreover, the manner in which this renewal lining and the temperature insulating elements are constructed, mounted and arranged within the shell permits of constructing this apparatus by means of materials which are of standard construction and thereby enables this apparatus to be manufactured at comparatively low cost.

80 I claim as my invention:

1. A drying and cooling apparatus comprising a rotary tubular shell, a temperature insulation engaging with the inner side of said shell, and a renewable lining engaging with the inner side of said insulation.

85 2. A drying and cooling apparatus comprising a rotary tubular metal shell, a plurality of longitudinal metal ribs secured to the inner side of the shell, temperature insulation interposed between said ribs and the shell, and lifting blades mounted on 90 said ribs.

95 3. A drying and cooling apparatus comprising a rotary tubular metal shell, a plurality of longitudinal metal ribs secured to the inner side of the shell, temperature insulation interposed between said ribs and the shell, and temperature insulation arranged on the inner side of said shell between 100 said ribs.

105 4. A drying and cooling apparatus comprising a rotary tubular metal shell, a plurality of longitudinal metal ribs secured to the inner side of the shell, temperature insulation interposed between said ribs and the shell, lifting blades mounted on 110 said ribs, and temperature insulation arranged on the inner side of said shell between 115 said ribs.

120 5. A drying and cooling apparatus comprising a rotary tubular metal shell, a plurality of longitudinal metal ribs secured to the inner side of the shell, temperature insulation interposed between said ribs and the shell, temperature insulation arranged on the inner side of said shell between 125 said ribs, and an inner metal lining arranged on the inner side of the insulation between adjacent ribs.

130 6. A drying and cooling apparatus comprising a rotary tubular metal shell, a plu-

- rality of longitudinal metal ribs secured to the inner side of the shell, temperature insulation interposed between said ribs and the shell, temperature insulation arranged 5 on the inner side of said shell between said ribs, and an inner metal lining arranged on the inner side of the insulation between adjacent ribs and detachably connected with the latter.
- 10 7. A drying and cooling apparatus comprising a rotary tubular shell, a plurality of longitudinal metal ribs of L-shaped form in cross section each having an outer base flange arranged circumferentially next to the shell and secured thereto and having an 15 inner attaching flange projecting radially

inward from the base flange, a temperature insulating member arranged between each base flange and the shell, temperature insulating segments arranged on the inner 20 side of the shell between said ribs, lifting blades secured to the inner edges of the radial flanges of said ribs, and metal lining sections engaging with the inner sides of said insulating segments and provided with 25 inwardly turned flanges which are secured to opposite sides of said radial flanges and blades.

In testimony whereof I affix my signature.

HARLAN W. HOW.
